UNITED STATES PATENT OFFICE.

JOSEPH LEVINE, OF CHICAGO, ILLINOIS, ASSIGNOR TO MET-L-WOOD CORPORATION, OF CHICAGO, ILLINOIS, A CORPORATION OF ILLINOIS.

JOINT FOR VENEERED PANELS.

Application filed April 23, 1927. Serial No. 185,955.

This invention relates to joints for veneered panels.

An object of the invention is to provide a construction wherein a plurality of plywood panels provided with metallic veneers may be connected together in such manner that the outer surfaces of the metallic veneers lie in a single plane, and the joint is rendered strong and neat in appearance.

Other and further objects of the invention will more clearly appear from the claims and description hereinafter following.

In the drawings, Figure 1 is a transverse sectional view through fragments of panels, and a portion of a supporting wall, showing the invention. Figure 2 is a top plan view of fragments of the panels showing inter-engaging portions of the veneer. Figure 3 is an enlarged fragmentary perspective view of one of the panels, and Figure 4 is an enlarged perspective view of a co-operating panel, showing the invention in connection therewith.

As shown in the drawings, two panels are provided denoted by the reference characters 5 and 6. The panel 5 comprises a plurality of layers of wood, commonly called ply wood, and secured to the outer surface of the panel is a thin steel veneer 7 in the form of a steel sheet, and interposed between the steel sheet and the layers of the ply wood is a fabric sheet, 8, all of these parts being secured together in a manner corresponding to that shown in Reissue Patent No. 14,349, granted to R. W. Burnett, September 11, 1917, wherein the fabric 8 has the function of compensating for the different rates of expansion and contraction of the ply wood and the sheet steel. The veneer 7 adjacent the edge 9 of the panel 5 is off-set inwardly as indicated at 10, approximately the thickness of the steel sheet 7, and is provided with an extension 11 which projects a suitable distance outwardly beyond the edge 9 of the panel 5.

The panel 6 includes layers of ply wood, a layer of fabric, and a sheet steel veneer in the same manner as the panel 5, and similar reference characters will be utilized to designate like parts of each. The sheet steel veneer 7 of the panel 6 lies in a flat plane throughout its extent and beneath the edge portion 12 of the sheet 7 the wood of the panel 6 is cut out as indicated at 13, in such manner that the edge portion or extension

11 upon the veneer 7 of the panel 5 fits within the cut-out portion beneath the steel sheet on the panel 6, while the edge portion 12 overlaps the extension 11 and fits into the off-set provided thereby, the extension 11 being of such length that the extreme edge 14 of the steel sheet on the panel 6 reaches to a point where the off-set 15 in the steel sheet 7 of the panel 5 is located. Securing elements indicated at 16 extend through the inter-engaged portions of the steel sheets of the panels 5 and 6, and extend through the ply wood into a support 17. The small trough which occurs between the off-set 10 and the edge 14 of the steel sheet 7 on the panel 6 is filled with solder indicated at 18 whereby the outer surface of the two panels 5 and 6 is rendered entirely smooth and flat, and the joint concealed from view, as well as being sealed against the entrance of moisture, the presence of the fabric layer preventing any strain being placed on the joint which might occur due to the different rates of expansion and contraction of the wood and metal layers.

By this construction a strong flat joint is obtained between the edges of the two sheets which may be locked in position by the same securing elements which are utilized to secure the panels in position on the support 17, the joint being sealed and rendered moisture proof by the solder disposed in the small trough formed at the off-set and adjacent edge of the steel sheets of the two panels.

While I have herein shown and described what I consider the preferred manner of carrying out the invention, the same is merely illustrative, and I contemplate all changes and modifications which come within the scope of the claims appended hereto.

1. In a structure of the character described, the combination with a plurality of panels disposed edge to edge, each having a metallic veneer secured thereto, the veneer of one panel terminating at the edge thereof, in a plane common with the remainder of said veneer, and the body portion of said panel being provided with a cut-out forming with the veneer a groove and the other of said panels having an integral off-set extension on the veneer thereof disposed in said groove, whereby the exposed surfaces of the veneers on the panels are disposed in a common plane.

2. In a structure of the character de-

- scribed, the combination with a plurality of panels disposed edge to edge each having a metallic veneer, secured thereto, the veneer of one panel terminating at the edge 5 thereof in a plane common with the remainder of said veneer, and the body portion of said panel being provided with a groove defined by a cut out portion of said panel and the veneer thereon, and the 10 other of said panels having an integral off-set extension on the veneer thereof disposed in said groove, whereby the exposed surface of the veneers on the panels are disposed in a common plane, and solder disposed between the off-set portion of one of said 15 veneers and the adjacent extremity of the veneer of the other panel.
3. In a structure of the character described, the combination with a plurality of 20 panels disposed edge to edge, each of which is provided with a veneer glued thereto, the veneer on one of said panels being off-set a distance corresponding to the thickness of the veneer, and the veneer on the other panel 25 disposed in the same plane throughout and overlapping the offset-portion of said first veneer, whereby the exterior surfaces of said veneers lie in a common plane.
4. In a structure of the character described, the combination with a support; of 30 a plurality of panels each provided with a metallic veneer, the veneer on one of said panels overlapping the adjacent edge of the veneer on the other panel, one of said veneers being off-set to dispose the outer surfaces of the veneers in a common plane, and securing means extending through the overlapped portions of said veneers through said 35 panels and into said support.
- 40 5. In a structure of the character described, the combination with a plurality of panels, each including a metallic veneer, and a sheet of fabric interposed between the veneer of each of said panels, and the panel 45 to which it is attached, the veneer of one of said panels being off-set and overlapped with reference to the veneer on the other of said panels whereby the outer surfaces of said veneers are disposed in a common plane.
- 50 6. In a structure of the character described, the combination with a plurality of panels, each including a metallic veneer, and a sheet of fabric interposed between the veneer of each of said panels, and the panel 55 to which it is attached, the veneer of one of said panels being off-set and overlapped
- with reference to the veneer on the other of said panels whereby the outer surfaces of said veneers are disposed in a common plane; a support; and securing means extending through the overlapped portions of said veneers, the material of which said panels are made, and into said support for rigidly securing said panels together and to 60 said support.
7. In a structure of the character described, the combination with a body portion having a plurality of metallic sheets secured thereto forming a veneer for said body portion, the adjacent edge portions of said 70 sheets being flat and overlapped and the edge portion of one of said sheets being off-set to one side of the plane defined by the body portions of said sheets and the edge portion of another sheet fitting into said 75 off-set whereby said second mentioned edge portion is disposed in a plane common with the plane defined by the body portions of said sheets, said body portion being cut out and forming with the veneer a groove for 80 the reception of said offset portion.
8. A metallic veneer comprising a plurality of metallic sheets having overlapping edges, one of the edges of one sheet being off-set to one side of the plane defined by the 85 body portion of said sheet a distance corresponding to one thickness of said veneer, and the edge of another sheet of the same thickness fitting into and overlapping said off-set whereby said last mentioned edge 90 portion is disposed in a plane common with the plane defined by the body portions of said sheets.
9. In a joint for veneered panels, the combination of a plurality of panels disposed 95 edge to edge, each having a metallic veneer secured thereto, the veneer of one panel terminating at the edge thereof in a plane common with the remainder of said panel, and the body portion of said panel being provided with a cut-out forming a groove, and the veneer of the other of said panels having a projecting tongue disposed in a 100 plane parallel with the veneer and arranged in line with and extending into said groove 105 of the first mentioned panel, for securing said panels together in edge to edge abutting relation in the same plane.

In witness that I claim the foregoing I have hereunto subscribed my name this 14th day of April, 1927.

JOSEPH LEVINE.
